UNITED STATES PATENT OFFICE.

JOSEPH A. MARTOCELLO, OF PHILADELPHIA, PENNSYLVANIA.

RAW-WATER ICE-MAKING SYSTEM.

Application filed September 1, 1922. Serial No. 585,604.

My invention relates to devices used for making ice in cans.

The purpose of my invention is to provide an air agitating system for cans having greater capacity for circulation within the cans.

A further purpose is to insure vertical alignment of air tubes within the can notwithstanding deviations of the tops of the tubes from vertical position because of improper placing of the bracket, air lateral or other tube support.

A further purpose is to obtain a maximum benefit from air discharged at a point above the bottom of the tube.

Further purposes will appear in the specification and in the claims.

I have preferred to illustrate my invention by selecting a type of apparatus which has proved to be practical, efficient and inexpensive and which at the same time well illustrates the principles of my invention.

Figure 1 is a top plan view showing several ice cans to which my invention is applied and in which the air tubes are supported by brackets.

Figure 2 is a vertical section taken upon line 2—2 of Figure 1.

Figure 3 is a vertical section showing the air tubes as depending from air laterals.

Figure 4 is an enlarged longitudinal section partly in elevation of a tube and its immediate connections illustrating my invention.

Figure 5 is a side elevation showing a modified form of flexible support for the tube.

Figure 6 is a broken vertical section through a lateral, connection, and tube such as appear in Figure 3.

Figure 7 is a broken side elevation of the lower part of an air tube.

In the drawings similar numerals indicate like parts.

In the freezing of ice in cans I have found it to be of great advantage to place the tube from which the agitating air is discharged vertically as distinguished from sloping it appreciably with respect to vertical position.

It is desirable also to discharge a small quantity of air from the side of the air tube so that when the bottom of the tube is frozen in, this side discharge will still keep the water in circulation. I have found that this side discharge from a vertical tube may be

made more effective for stirring purposes if the air be discharged at a downward slant.

My invention has been made with a view to taking care of these two features of tube position and air discharge.

In Figures 1 and 2 I have illustrated a conventional arrangement of ice cans shown at 10 with respect to air laterals 11, flexible connecting pipes 12 and nozzles 13 in fluid communication with the upper ends 14 of distributing air pipes or tubes. The tubes are supported in this view from the side walls of the cans by brackets 15 which may be of any desired type and the air supply may be controlled by valves at any suitable point such as at 16.

It has been customary to mount these tubes rigidly upon the support for various reasons, one of which is in order to gain the advantage of stiffness for a terminal such as 17 to receive a thawing needle. As a result the angle of the tube within the can is altered with every shift in angle of the support. Where a bracket, for example, is used and the thickness of the can side is not the same as that for which the bracket has been intended, the free end of the bracket will be lifted in the case of a thicker wall and will be lowered in the case of a thinner wall, with consequent variation in the position of the air-agitation pipe from the vertical position which I regard as highly desirable.

I prefer to use a bracket support and to secure the upper pipe terminal rigidly in the bracket as by the clamp 18 engaging the upper end of the pipe upon which the receiving device for the thawing needle is mounted, illustrating a construction of bracket and a mount for the upper end of the pipe substantially the same as shown in my application for Air pipe support for freezing systems, Serial No. 526,460, filed January 2, 1922. However, I recognize that my invention is of advantage with any other form of this structure which would give variant angular position to the air pipe with differing conditions met with in service and illustrate in Figure 3 another form of support for the tube to emphasize this.

In order to overcome the objectionable cant which these and other varying service conditions may thus give to the air-agitating pipe, I support the major portion of the length of the pipe or all of the pipe upon a flexible connection 19 which is shown in Fig-

ures 2 and 4 as comprising a rubber coupling 20. It couples the lower end of the upper pipe section to the upper end of the tube 21, or to a support for the tube, using the flexibility of this coupling to hang the tube or the lower tube section in a vertical position.

In Figure 5 an alternative construction is shown in the form of a metallic flexible connection 22 secured to the lower end of 10 the upper section and supporting the lower section 21. This metallic coupling may be soldered to the pipe ends if desired.

The coupling which I show may be located above the water and ice level in the can 15 but on account of its use where it is likely to get wet it should be capable of resisting water in any event. It must also, of course, retain the agitating air to avoid waste of air and also to maintain the air pressure 20 for agitation.

In Figure 3 the tubes are connected directly with the air lateral through a fitting 23, screwed into the lateral against a soft or shaped washer 24 and terminating within 25 the lateral in a reducing intake 25.

The tube 21' is suspended beneath this fitting 23 by a flexible coupling engaging the lower part of the fitting at 26 and the upper end 27 of a nozzle 13' adapted to 30 fit within a tube terminal 17 suitable for receiving a thawing needle and to which the tube 21' is attached. The tube 21' may enter the coupling directly if desired omitting the nozzle and the fitting 17.

35 The thawing needle terminal is accessible upon withdrawal of the nozzle, when the tube 21' has been frozen in.

In either form the flexible mounting of the tube permits the tube to assume a vertical 40 position notwithstanding change in the direction of the tube section, fitting or other part from which it hangs.

In the side of the air tube 21 well above the bottom I provide an aperture small 45 enough not to unduly reduce the pressure so as not to interfere appreciably with the discharge of air through the bottom of the tube, but capable of delivering sufficient air for stirring purposes when the air no longer finds outlet through the bottom of the pipe. It may be smaller than the reducing intake. When the water surrounding the bottom of the tube is frozen this side outlet 28 becomes effective at an increased pressure to maintain 50 the stirring in the comparatively small

space about the tube where the water is not yet frozen. I secure maximum results in stirring by this side air outlet by forming it at an angle downward, so that the velocity of the air will cause the bubbles of air discharged to free from the tube wall and to extend as far outwardly from the tube as possible with the existing air pressure. The downward and outward slope given the discharging air insures a maximum range for 60 the air before it starts to rise through the water.

The discharge opening at the side is made small enough so that the leakage is not great during the time air is coming out of 70 the lower end of the tube. As soon as air ceases to flow from the lower end of the tube the pressure of the air within the tube (which up to that time has never exceeded that necessary to overcome the weight of 75 the water above the end of the tube) rises and if the side discharge outlet be smaller than the reducing valve or intake used (as I prefer) may become equal to that in the air lateral.

80 As a result the air is discharged from the side outlet at a velocity great enough to free the bubbles well from the sides of the tube and to give good circulation adjacent to the tube.

85 It will be obvious that in view of my disclosure herein others skilled in the art will see modifications and variations of my invention by which a large part or all of its advantage of my structure may be obtained 90 without copying it and it is my purpose to include herein all such changes as come within the reasonable spirit and scope of my claims.

Having thus described my invention what 95 I claim as new and desire to secure by Letters Patent is:—

1. In a raw water system, a can, and an air pipe extending down into the can and having a bottom opening and apertured at 100 the side extending diagonally downward from the inside of the pipe.

2. In a raw water system, a can, an air supply having a reducing section therein and an air pipe extending down into the 105 can, open at the bottom and having a side opening smaller than the opening in the reducing section.

JOSEPH A. MARTOCELLO.
